UNITED STATES PATENT OFFICE.

CHARLES GROOS, OF SAN FRANCISCO, CALIFORNIA.

SCREW-DRIVER.

1,055,031.

Specification of Letters Patent.

Patented Mar. 4, 1913.

Application filed August 5, 1912. Serial No. 713,209.

To all whom it may concern:

Be it known that I, CHARLES GROOS, a citizen of the United States, residing at San Francisco, in the county of San Francisco and State of California, have invented new and useful Improvements in Screw-Drivers, of which the following is a specification.

The object of my invention is to provide a screw driver of such construction that, 10 while not materially diminished in strength, a screw may be screwed in or out merely by a torsional force applied to the screw driver, thus dispensing with the necessity of applying direct or longitudinal pressure thereto.

15 It is a matter of common experience that, in the majority of cases, the greater part of the force exerted in screwing a screw in or out is expended in maintaining the screw driver in engagement with the screw. Unless pressure, and sometimes very great pressure, is applied to the screw driver, its operating end will slip out over the walls of the groove in the screw head, involving loss of time in re-applying the screw driver to 20 the screw. Often the surface of the material worked upon is scratched and marred by the point or edge of the screw driver so slipping. After a screw driver has once slipped in this manner, it is more difficult to 25 prevent its recurrence, owing to the fact that the edge of the groove has become rounded off, and offers less resistance.

By so constructing a screw driver that torsional force applied thereto tends to hold 35 it to the screw the more securely the greater is the force applied, the necessity of direct inward pressure on the screw driver is eliminated, and the force necessary to be exerted is only that required to turn the screw in the 40 material.

In the accompanying drawing, Figure 1 is a side view of a screw driver constructed in accordance with my invention; Fig. 2 is an enlarged perspective view of the operating end thereof; Figs. 3, 4, 5 and 6 are views, similar to Fig. 2, of modified forms 45 of the invention.

Referring to the drawing, 1 indicates one form of my improved screw driver. Upon 50 each side of the operating terminal portion of said screw driver there are formed two rounded grooves 2, commencing near the central longitudinal line of said side, and increasing in depth and width to the respective edges thereof. The outer or lower wall

3 of each groove terminates so close to the end of the corresponding edge of the screw driver, that the portion 4 of the face of the screw driver engaging the wall of the groove in the screw is very small and forms 60 a tooth, more or less pointed. Also the screw driver is made of material harder than the screw with which it is used. Consequently, on torsional pressure being applied in the proper direction to the screw 65 driver, the pressure is applied to the wall of the groove in the screw from a surface of the screw driver of such small extent and said pressure is so concentrated that it produces 70 a slight indentation therein, and longitudinal movement of said tooth 4 along said wall is prevented. No inward or downward pressure is therefore required to maintain the screw driver in engagement with the screw, but only a rotational pressure. It 75 will be observed that the strength of the screw driver is not materially diminished since at the center of its sides, where the greatest torsional strain occurs, its thickness is not reduced from that of the ordinary 80 form. It will also be observed that to achieve the desired result, the thickness of the screw driver is not increased, which would prevent it from being used with 85 screws of the ordinary size.

In the modification shown in Fig. 3, the groove is shown as extending in one direction only on each side from the middle portion of said side to the edge thereof. In the modification shown in Fig. 4, the groove 8 is angular. In the modification shown in Fig. 5, the groove 9 is of uniform depth throughout. This is also the case in the modification shown in Fig. 6, in which the groove 9 is angular.

I am aware that, to obtain the result aimed at by my invention, it has been proposed to form the screw driver with a point or edge projecting beyond the plane of the side of the screw driver, but this is objectionable, because it necessitates the screw being formed with a wider groove, thus unduly weakening the head of the screw or else reducing the thickness of the bit unduly weakening the screw driver if used with 105 screws now on the market.

I claim:

1. A screw driver having formed in a surface near its operating end, a groove extending from one side of the middle of said 110

surface to the adjacent edge of the screw driver, the middle portion of said surface, at the same distance from the operating end, being flush with the top of the groove.

5 2. A screw driver having formed in a surface near its operating end a groove extending from one side of the middle of said surface to the adjacent edge of the screw driver, and increasing gradually in depth,
10 the middle portion of said surface, at the

same distance from the operating end, being flush with the top of the groove.

In testimony whereof I have hereunto set my hand in the presence of two subscribing witnesses.

CHARLES GROOS.
